CLAIM

The ornamental design for a gaming chair, as shown and described.

DESCRIPTION

FIG. 1 is a left elevational view a gaming chair showing our new design;

FIG. 2 is a front side elevational view of thereof;

FIG. 3 is a bottom plan view thereof;

FIG. 4 is a top plan view thereof;

FIG. 5 is a left perspective view thereof.

(Continued)

FIG. 6 is a right side elevational view thereof;
FIG. 7 is a back view thereof; and,
FIG. 8 is a right perspective view thereof.
The broken lines shown in the drawings are for the purpose
of illustrating portions of the article and form no part of the
claimed design.

1 Claim, 8 Drawing Sheets
